UNITED STATES PATENT OFFICE.

MILTON H. SHOENBERG, OF SAN FRANCISCO, CALIFORNIA.

DESIGN FOR A SOCKET-INTERRUPTER.

57,159.

Specification for Design.

Patented Feb. 22, 1921.

Application filed June 2, 1920. Serial No. 386,093. Term of patent 14 years.

To all whom it may concern:

Be it known that I, MILTON H. SHOENBERG, a citizen of the United States, and a resident of the city and county of San Francisco, State of California, have invented a new, original, and ornamental Design for a Socket-Interrupter, of which the following is a specification, reference being had to the accompanying drawings, forming a part thereof.

Figure 1 is a top plan view of my interrupter.

Fig. 2 is a side view with the insulating ring in section.

Fig. 3 is a bottom plan view.

I claim:

The ornamental design of a socket interrupter substantially as shown.

MILTON H. SHOENBERG.
